VERTICAL FIRE TUBE STEAM BOILER

Charles T. Denker and John R. Moore, Chicago,
Ill., assignors to The Calefactor Corporation,
Chicago, Ill., a corporation of Illinois

Application February 9, 1946, Serial No. 646,519

3 Claims. (Cl. 122—122)

1

This invention relates to steam-boilers and more particularly to the combination fire tube-water tube type of steam boiler.

Fire tube-water tube boilers are, of themselves, relatively old in the art. However, although the fire tube-water tube boilers heretofore known to the art have compared favorably in efficiency with other types of boilers also heretofore known, the efficiency of the boilers has been undesirably low, and it is an object of our invention to construct a boiler having a greater over all efficiency than the fire tube-water tube boilers heretofore known to the art.

In fire tube-water tube boilers heretofore known to the art the construction has been such that direct heat transfer relationship between the combustion chamber itself and water introduced into the boiler was poor. In the usual form of boiler heretofore known to the art, a water header is embodied in the proximity of the combustion chamber and may or may not contact the combustion chamber, and if it does contact the combustion chamber, it does so over only a very limited area. It is a general object of our invention to construct a boiler providing good heat transfer relationship between water introduced into the boiler and the combustion chamber thereof, and an object ancillary thereto is to associate the elements of our boiler in such a manner that water introduced into the boiler may be in direct contact with a substantial portion of the outer surface of the combustion chamber thereof.

One of the advantages inherent in fire tube-water tube type boilers is that heat transfer may be made to opposite sides of a relatively thin body of water within the water tubes, so that what heat is transferred is absorbed by a relatively small mass of water and the water, or the steam formed therefrom, is heated to a relatively high temperature. However, efficiency of a boiler depends upon, among other things, what percentage of the heat generated by the combustion of a certain amount of fuel is utilized in heating the water, the greater the percentage of the heat actually absorbed by the water and steam the greater the efficiency of the boiler. This has heretofore posed a difficult problem to the art because, to obtain good combustion within the combustion chamber of a boiler, it is necessary that the flow of gases or combustion effluent not be restricted to such an extent that insufficient draft is realized through the combustion chamber. Heretofore, in fire tube-water tube boilers known to the art, the construction, in general, has been such that the principal heating was

2

accomplished by the flow of hot gases directly from the combustion chamber in parallel through the fire tubes and over the outside of the water tubes, part of the gases, flowing from the combustion chamber, passing through the fire tubes and the other part of the gases, flowing from the combustion chamber passing over the outside of the water tubes. This construction as shown by the prior art has been inefficient because, among other reasons, if the gases were allowed to flow freely, so as to obtain proper draft through the combustion chamber, the velocity of the gases through and over the water tubes was so great, and the distance that the gases traveled in heat exchange relation to the water or steam was so short that a proper amount of heat was not withdrawn from the hot gases and transferred to the water or steam before the hot gases were exhausted to the atmosphere, and, as a result, a great amount of heat escaped up the chimney and was lost to the atmosphere; and, on the other hand, if baffles or other means were used to retard the flow of gases through and over the water tubes sufficiently that the gases remained in contact with the water tubes for a sufficient length of time to effect a transfer of the proper amount of heat from the gases to the water or steam, the draft through the combustion chamber was reduced to such an extent that proper combustion was not obtained and, therefore, a loss of efficiency resulted. Therefore, it will be noted that in a fire tube-water tube boiler of the type heretofore known to the art it has been impossible to effect both an efficient flow of hot gases, so as to provide a proper draft through the combustion chamber, and also the most efficient transfer of heat from the hot gases to the water and steam, and, therefore it was necessary to compromise between the two for an average efficiency. It is an object of our invention to construct a fire tube-water tube boiler in such a manner that an efficient heat transfer may be effected from the hot gases to the water, and, also that the velocity of the hot gases or combustion products will be sufficient that the desirable and proper draft through the combustion chamber may be effected. An object of our invention ancillary to this is to associate the elements of our boiler in such a manner that all the gases pass through all the heat exchange mediums thereof, in series.

A further object of our invention is to associate the elements of our boiler that from the formation of hot gases in the combustion chamber and throughout the passage thereof through

the boiler they are in good heat exchange relationship with water or steam.

Another object of our invention is to construct a boiler in such a manner that all the internal elements thereof, in which hot gases are formed or through which they pass, are substantially surrounded by water or steam in good heat exchange relation therewith.

Yet another object of our invention is to construct a fire tube-water tube boiler wherein all 10 the gases flowing from the combustion chamber flow through the fire tubes and all the gases flowing from the combustion chamber flow over the outside surface of the water tubes as distinguished from part of the gases flowing through 15 the fire tubes and another part flowing over the outside of the water tubes.

It is a further object of our invention to associate the elements of a fire tube-water tube boiler in such a manner that hot gases flow over 20 the outer surface of the water tubes transversely to the longitudinal axis thereof. Another object of our invention is to construct a boiler wherein there is a minimum of structure separating the hot gases from the water 25 and steam.

Yet another object of our invention is to provide a boiler of simple and economical construction, which will be efficient in use and will give long service with a minimum of repair and maintenance.

Other and further objects of the present invention will be apparent from the following description and claims and are illustrated in the accompanying drawings which, by way of illustration show a preferred embodiment and the principle thereof and what we now consider to be the best mode in which we have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a side elevational view, partly in section, of a fire tube-water tube boiler embodying the principles of our invention.

Fig. 2 is a sectional view taken substantially on the line 2-2 of Fig. 1; and

Fig. 3 is a sectional view taken substantially on the line 3-3 of Fig. 1.

The boiler shown in the accompanying drawings embodies an outer boiler casing or shell 10 having a top wall 11, front wall 12, bottom wall 13, side walls 14 and 15 and a rear wall 16. The walls may be made of any suitable material such as, for example, sheet steel, and any walls which when the boiler is installed for use, are in close proximity to walls or other structural members of a building or the like, may be insulated with a suitable insulation such as the sheet insulation 17 shown affixed to the rear wall 16.

The outer boiler casing 10 may be considered to embody, in general, four heating areas or heating chambers, A, B, C and D; the lower heating chamber A including a lower combustion chamber or fire box 18 and a lower water header 19; the upper heating chamber B including an upper combustion chamber or flame box 20 and a steam header or steam dome 21; the intermediate heating chamber C interconnecting the lower heating chamber A and the upper heating chamber B and comprising water tubes 22, fire tubes 23 and a transverse exhaust duct or water

tube housing 24; and a heating flue or vertical heating chamber D, including a vertical water leg 25, and a vertical exhaust duct 26 interconnecting the flame box 20 and the transverse exhaust duct 24.

The lower combustion chamber 18 has side walls 27 and 28, a top wall 29, a bottom wall 30, and a front wall 31 which may be constructed of any suitable material such as, for example, sheet steel. The rear edge portion of the lower combustion chamber 18 is attached to the rear wall 16 of the outer casing 10, in air tight connection therewith, by any suitable means such as, for example, welding, and a portion of the wall 16 thus forms the rear wall of the combustion chamber 18. The flame box 20 is in the form of a conduit or exhaust duct having a lower wall 32, an upper wall 33 and side walls 34 and 35, the rear edge portions of which walls are attached to the inner surface of the rear wall 16 of the outer casing 10 in an air tight connection by any suitable means such as welding. The front edge of the upper combustion chamber 20 is attached to the upper end portion of the vertical exhaust duct 26 in air tight connection therewith by any suitable manner such as welding. The vertical exhaust duct 26 has a rear wall 37, a front wall 38, side walls 39 and 40 and a bottom wall 41. The upper end portion of the vertical exhaust duct 26 is open to, and attached to the upper combustion chamber 20. The vertical exhaust duct has an opening 41a formed in the rear wall 37 thereof through which, as is set forth more specifically hereinafter, communication is provided through 35 the vertical exhaust duct 26 into the transverse duct 24. The transverse duct 24 has a lower wall 42, an upper wall 43, side walls 44 and 45 and a front wall 46. The rear edge portion of the transverse duct 24 is attached to the inner surface of the rear wall 16 of the outer shell 10 in an air tight connection by any suitable means such as, for example, welding. The front wall 46 of the transverse duct 24 has an opening formed therein which is complementary to the opening 41a formed in the vertical duct 26, and peripheral edge portions of the openings in the vertical duct 26 and the transverse duct 24, respectively, are connected by a collar 47 which may be welded thereto. The plates 46 and 37 are 40 also connected at spaced points by tubular stay bolts 46a, as shown in Figs. 1 and 3 so as to prevent bulging thereof. These tubular stay bolts may be brazed to the plates 46 and 37.

The top wall 33 and side walls 34 and 35 of the flame box 20, the front wall 38 and the side walls 39 and 40 of the vertical duct 26, the side walls 44 and 45 of the transverse duct 24, the side walls 27 and 28, the bottom wall 30 and the front wall 31 of the lower combustion chamber 18 are each attached to the respective adjacent walls of the outer casing 10 by means of suspension bolts 48 and are supported thereby in spaced relation to the outer shell 10.

The lower fire box 18 is interconnected to the flame box 20 by means of the fire tubes 23. The lower end of the fire tubes 23 are inserted through the upper wall 29 of the lower fire box 18 and attached in sealed relation thereto by any suitable means such as by welding.

Suitable fuel such as, for example, commercial water gas, natural gas, or the like may be mixed with air and fed by any suitable means, such as, for example, burners 128, Figs. 1 and 2, connected to conventional feeding apparatus 129 shown in Fig. 1. It will be understood that the

burners 128 and the feeding apparatus 129 are shown in the drawings to illustrate a preferred embodiment of our invention and not by way of limitation thereto, and that other types of burners and feeding apparatus may be used without departing from the purview of our invention.

The hot gases and other combustion effluent resulting from combustion of fuel within the lower combustion chamber 18 flow upwardly through the fire tubes 23 into the flame box 20 from which they flow downwardly through the vertical exhaust duct 26, substantially horizontally through the transverse duct 24 from which they pass through an opening 49, provided in the rear wall thereof into a flue or chimney 50 and are exhausted to the atmosphere. Thus it will be noted that the flame box 20, the vertical exhaust duct 26 and the transverse exhaust duct 24 each of themselves, form an efficient heat exchange element having good heat exchange relationship with water or steam in the boiler, and together form an exhaust duct through which hot gases or combustion products can efficiently flow from the combustion chamber and fire tubes to the chimney 50 and be exhausted to the atmosphere.

It will be noted that, although we prefer to use liquid or gaseous fuels, our invention is not limited to the use thereof, and solid fuels may be used, if desired, by the insertion of proper grates and other necessary equipment all of which are old and well known to the art.

Water is introduced into the outer shell 10 through an inlet 51 provided in the bottom 13 thereof and flows up into the water header 19 surrounding the lower combustion chamber 18 on all sides except the rear side thereof and normally rises into the water leg 25 surrounding the transverse duct 24 and the vertical duct 26 on all sides except the rear side of the transverse duct 24. The water tubes 22 are carried by and extend vertically through the transverse duct 24, with the upper and lower end portions of the water tubes 22 extending through the top and bottom walls 43 and 42 respectively, of the transverse duct 24 and being attached thereto in a sealed connection by any suitable means such as, for example, by welding. Each of the water tubes 22 are positioned to encircle a fire tube 23, the inner wall of the water tubes 22 being spaced outwardly from the outer wall of the fire tubes 23, as best shown in Fig. 3. It will be noted that when water is introduced through the inlet 51 into the water header 19 and rises into the water leg 25, that water also rises into the water tubes 22 surrounding the fire tubes 23. Thus it will be noted that with combustion taking place within the lower fire box 18 and the outer shell thereof heated by the combustion, the water entering the boiler is initially heated in the water header 19 while it is flowing from the inlet 51 into the water tubes 22 and the water leg 25 and that the thin layer of water within the water tubes 22 is further heated from the inside by any continuation of the combustion which takes place within the fire tubes 23 and by the passage of hot gases vertically through the fire tubes 23 into the upper fire chamber 20.

If suitable provisions were not made, water flowing into the water header 19 would, choosing the path of least resistance, tend to rise into the water leg 25 rather than into the relatively restricted areas between the water tubes 22 and the fire tubes 23. To prevent this and to assure

proper feeding of water into the water tubes, we provide a panel 60 which extends outwardly from the bottom wall 41 of the transverse duct 24 and the vertical duct 26, respectively, and underlies the water legs 25. The panel 60 has openings 61 formed therein which are of sufficient size that the rise of water into the water legs 25 is partially restricted so that water tends to rise equally from the water header 19 into the water tubes 22 and the water leg 25.

The exhaust gases which enter the flame box 20 from the upper end portion of the fire tubes 23 pass downwardly through the vertical exhaust duct 26, which is heated thereby, and additional heat is thereby supplied to the water which surrounds the vertical duct 26, such as, for example, the water in the water leg 25. From the vertical exhaust duct 26 the exhaust gases pass through the opening 41a and the tubular stay bolts 46a into the transverse duct 24 in which they pass substantially horizontally across the outside of the water tubes 22, thereby heating the water and steam within the water tubes 22 from the outside thereof, and pass out through the opening 49 into the flue or chimney 50 from which they escape into the atmosphere.

Visual checks may be constantly made on the temperature of the steam and the level of the water within our boiler by referring to the thermometer and the water level gage attached to connections 53 and 54, respectively, shown in Fig. 2.

From the foregoing it will be noted that the water within the water tubes 23 is heated both from within and without by hot gases passing through the fire tubes 22 and the exhaust duct 24 respectively. Also it will be noted that the water vapor or steam which passes upwardly from the water tubes 22 or the water leg 25 into the steam header 21 is further heated by the combustion effluent and hot gases which pass through the upper combustion chamber 20. From the steam chamber 21, the steam passes from the boiler 10 through the outlet 52 from whence it circulates into the heating system or other system in which it is used.

Furthermore it will be apparent, from the foregoing, that the flow of gases from the lower combustion chamber 18 through the fire tubes 23, the upper fire box 20, the vertical exhaust duct 26, the transverse exhaust duct 24, and the chimney or flue 50 to the atmosphere is relatively unrestricted but is so designed that efficient heat transfer is effected between the combustion products and the water and steam from the initial combustion within the lower fire box 18 and throughout the passage of the combustion products through the boiler from the lower fire box 18 until the gases enter the chimney or flue 50. Furthermore, it will be noted that the water which enters from the inlet 51 is initially heated within the water header 19 so that the water which enters the water tubes 22 has been pre-heated and that therefore the heat on both sides of the relatively thin layer of water tubes 22 furnished by the gases passing through the fire tubes 23 and through the transverse duct 24 is fully capable of transforming the water within the water tubes 22 to steam at relatively high temperatures for passage into the steam header or steam dome 21.

Thus it will be noted that our invention provides a boiler wherein all the exhaust gases pass successively through all the heat exchange elements therein so that good heat exchange re-

lationship between the gas and the water or steam is prolonged and a maximum heat exchange is effected.

Also, it will be noted that our invention provides an efficient boiler wherein, although the exhaust gases are relatively unrestricted in their flow to the atmosphere so that a good draft through the combustion chamber thereof is effected, the passage of these gases is so laid out and the elements of our boiler are associated with each other in such a manner that efficient heat transfer is realized from the combustion products to the water and steam to be heated so that a minimum of heat escapes through the flue 50 to be lost to the atmosphere.

Furthermore, it will be noted that by varying the size of our boiler unit, without changing the principles of operation thereof, our boiler unit may be equally well adapted either for commercial or residential heating purposes.

Also it will be noted that the present invention accomplishes its intended objects some of which have been specifically referred to hereinbefore and other of which will be apparent from the foregoing description taken in conjunction with the accompanying drawings.

Hence, while we have illustrated and described the preferred embodiments of our invention, it is to be understood that these are capable of variation and modification and we therefore do not wish to be limited to the precise details set forth, but desire to avail ourselves of such changes and alterations as fall within the purview of the following claims.

We claim:

1. A boiler comprising an outer casing, a lower combustion chamber mounted within said casing and having outside walls spaced inwardly from walls of said casing, a flame box mounted within said casing above said combustion chamber and having outside walls spaced inwardly from walls of said casing, fire tubes interconnecting said combustion chamber and flame box, an exhaust duct mounted within said casing between said combustion chamber and flame box and having outside walls spaced from walls of said outer casing, means for transferring exhaust gases from said flame box to said exhaust duct, water tubes mounted within said casing around said fire tubes and extending through said exhaust duct, and means for introducing water into said outer casing in direct contact with said lower combustion chamber, and means for exhausting steam from the upper end portion of said casing.

2. A boiler comprising an outer casing having top, bottom, front, rear and side walls, a lower combustion chamber mounted within said casing and supported thereby, an upper chamber mounted within said casing and supported thereby, vertically extending fire tubes interconnecting said upper and lower chambers, a substantially horizontally extending exhaust duct mounted in said outer casing and supported thereby in position between said upper and lower chambers, said lower chamber, said upper chamber and said horizontal exhaust duct each having top, bottom, front and side walls and having the rear edges of said top, bottom, and side

walls attached to the inner surface of said outer casing in air tight connection therewith, a flue interconnecting said horizontally extending exhaust duct and said upper combustion chamber, water tubes surrounding said fire tubes and extending through said horizontally extending exhaust duct, said chambers and said exhaust duct being disposed relative to each other and to said casing so as to afford water-receiving spaces in said casing between predetermined portions of said chambers and said exhaust duct and between said casing and predetermined portions of said chambers and said exhaust duct and which spaces are so disposed that when said spaces are full of water said water is in direct contact with the top, bottom, front and side walls of said combustion chamber, the bottom, front and side walls of said horizontally extending exhaust duct, and the outer surfaces of said fire tubes within said water tubes, and means for feeding water into said water-receiving spaces in said outer casing.

3. A boiler comprising a casing, a lower fire box mounted in said casing and partially spaced therefrom, an upper flame box mounted in said casing and partially spaced therefrom, fire tubes connecting said fire box with said flame box, a water header comprising the space between said fire box and said casing and substantially surrounding the top, bottom and side portions of said fire box, a steam header comprising the space between said flame box and said casing and substantially surrounding the top, bottom and side portions of said flame box, means for introducing water into said water header into intimate heat exchange relationship with said fire box, water tubes surrounding said fire tubes and connecting said water header with said steam header, a panel mounted in the lower end portions of said water tubes within said casing, said panel having openings therein for the passage of water between said headers exteriorally of said water tubes, and means including an exhaust duct for exhausting hot gases from said flame box to the atmosphere, said last named means being adapted to guide the hot gases over the outside surfaces of said water tubes in intimate heat exchange relationship therewith.
